FURNACE CHARGING APPARATUS

Zebulon W. Whitehouse and Oscar M. Schulze, Canton, and Hans F. Fischer, Cleveland, Ohio, assignors to Republic Steel Corporation, Cleveland, Ohio, a corporation of New Jersey

Application July 17, 1951, Serial No. 237,111

12 Claims. (Cl. 214—29)

In present types of furnace charging apparatus, e. g. such as used in charging open hearth or electric furnaces with scrap or other material, it is common to employ a so-called peel which is generally a heavy arm of tapered cylindrical or like shape with an enlarged head member that is adapted to engage a lug on a box or container loaded with material to be charged into the furnace. The peel is usually supported on a vehicle or like means and is there arranged with a pivoted mounting to rock the head member up and down, all in such a way that the charge container can be readily picked up and carried into the furnace to unload the container. The vehicle on which the peel is mounted is movable toward and away from the door of the furnace and also sometimes may travel on tracks running parallel to the front of the furnace in such fashion that several furnaces which are located side by side may be charged with the same apparatus.

An object of the present invention is to provide more convenient and commodious charge-handling and unloading apparatus, which may be adapted to use on currently employed and basically advantageous types of charging machines, without changing the structure of the peel itself. In such machines the peel, which may be defined as of standard design in consisting of a long, essentially unitary arm and having a single head member at the end, may be sturdily constructed by casting or forging operations or the like, and constitutes a very simple and rugged element of the equipment. Indeed as explained below, the present improvements obviate the need for an arrangement whereby the head member or part or all of the peel body is rotatable relative to the remainder of the peel or its mounting; in any case no less simple and sturdy peel is needed than is represented in the equipment now generally used. In other words this invention entails apparatus which may be mounted on the vehicle that carries the peel, or indeed on the peel assembly itself but externally to the peel, and which will effect greatly improved results in charging a furnace.

Another object of this invention is to eliminate the complication and extra machinery which has been necessary heretofore in order to rotate the peel or its head member or portion about its axis, while at the same time the present, improved apparatus affords a far more effective and satisfactory charging operation. The procedure of rotating the peel has been heretofore necessary because of what has been the standard practice in use of charging equipment. The scrap, e. g. scrap iron, steel or other material to be charged, is loaded in relatively small, box-like containers, which are then brought up to the front of the furnace, in succession, on cars. There the peel carries each charging box into the furnace where, by the described rotation, the box is rotated to discharge the contents. This procedure necessitated machinery for rotating the peel (or a part of it) about its longitudinal axis while it was supporting a heavy load, but such arrangements are now eliminated by the present invention.

In providing improved means for discharging containers inside the furnace without rotating or tipping them there, the invention serves another and particularly important object, namely that of enabling use to be made of a large-sized charging container, e. g. having from four to six times the capacity of the present conventional box. The advantages gained from using a much larger box or container are numerous. Among these advantages are the fact that fewer charging boxes are necessary, i. e. to charge the same load; hence fewer charging cars to carry the containers into place in front of the furnace are necessary. More space and less confusion or congestion on the open hearth charging floor results from the use of fewer cars per charge, and there is less interference of one furnace operation with adjoining furnaces. The increase in size of containers also means that each can be more densely loaded with scrap (which usually comprises metal pieces or fragments of widely varying size and shape), so that there is a larger load per cubic foot of box. Furthermore, much scrap may be charged without any preparation, e. g. in place of prepared or baled scrap; by reason of the larger cross section of the container, the scrap can be loaded more easily in the stockhouse, and the trimming operation is simplified and in many cases eliminated. Since there is better loading of the larger box, spillage from the boxes is greatly reduced, and in turn, the weight of the material charged in the furnace is more accurate. With fewer cars needed to convey the same amount of scrap, less motive power is required for each drag or train, thereby expediting delivery of scrap, while maintenance is reduced by the less frequent use of the cars.

Additional objects are also achieved in relation to the primary object of providing improved, simple and exceptionally efficient means to eliminate the turning of the container in order to discharge the contents. Thus elimination of such turning brings several further advantages, among which is the fact that there is no damage to the roof of the furnace as has frequently occurred by impact of the box when it turned over. In addition, there is no loss of charge containers due to their slipping off the peel into the furnace during the process of turning. The present apparatus also obviates the extra, severe strains on the peel and charging mechanism which stemmed from the flopping or shifting of the box when the peel was turned. Finally, the avoidance of turning of the box permits the charge of scrap or other material to be piled higher in the furnace; thus a greater amount of scrap may be charged at one time, reducing the number of charges necessary for one heat of the furnace.

To these and other ends, an advantageous embodiment of the invention is described below and shown in the drawings, by way of example to disclose the features and principles of improvement.

Referring to the drawings:

Fig. 1 shows a plan view of a peel and the front of its support with a pusher mechanism, and a container partially in section, taken along the line 1—1 in Fig. 2 looking in the direction of the arrows;

Fig. 2 shows a side view of the same apparatus as that shown in Fig. 1, with the charge container in section, taken along line 2—2 of Fig. 1 looking in the direction of the arrows;

Fig. 3 is a view partly in cross section showing the pusher mechanism, taken along line 3—3 of Fig. 2 looking in the direction of the arrows;

Fig. 4 is a fragmentary, enlarged, cross sectional view showing one of the upper rollers for a pusher arm, taken along line 4—4 of Fig. 2 looking in the direction of the arrows;

Fig. 5 shows an exploded perspective view of the charg-

ing container, false back, head of the peel, and pusher heads, illustrating the lug on the container and lugs on the false back; and

Fig. 6 is a schematic side view of the peel supporting vehicle with fragmentary showing of its guides and supporting framework.

The following is a specific description of the embodiment of the invention which is illustrated in the figures of the drawings.

Fig. 1 shows a charge container 11 in position in front of the door 12 of a furnace 13, e. g. an open hearth or other furnace (for producing steel) into which the load of scrap (not shown) carried in the container 11 is to be deposited. The charge container is a box-like, steel structure having an open forward end and a false, i. e. horizontally movable back 14 opposite the open end. This false back 14 (see also Figs. 2 and 5) has two guiding support members 15 extending forwardly, and carries, on its rear face, two lugs 16 which are adapted to be engaged by the head members 17 of the pusher mechanism, generally indicated by reference numeral 18. The charge box or container 11 is made of comparatively thin side walls 22 and a somewhat heavier bottom 22' supported by a rugged framework 19; while the box may have any desired dimensions, a special advantage of the invention, as explained above, resides in making it much larger than the boxes now customarily used. The charge box 11 is carried into position in front of the furnace on a car 20 partially shown in Fig. 2. As may be seen the car 20 travels sideways in front of the furnace on rails, only one of which is illustrated at 21, the arrangement of the track and cars for bringing up successive charging boxes being generally or functionally the same as with conventional charging equipment.

There is attached to the charge container proper, by means of being welded into an integral part of the same, a lug 23 for removable engagement by a peel head as described below. Specifically, the lug 23 is embodied with, and supported by, certain non-movable back structure of the box 11, which includes cross bars 23' at the top and which is appropriately open at each side of the lug 23 for rearward projection of and full access to the lugs 16 of the false back 14. The interrelation of the false back, its lugs, and the lug 23 of the charge container itself will be more fully explained below in connection with Fig. 5.

The pusher mechanism 18 is mounted on a body or frame member 24 which is pivotally attached to a charging vehicle framework 25 by means of a horizontal shaft 26. The member 24 actually constitutes a part of the peel assembly of the charging machine, which also includes a forwardly extending peel arm 27 having a rugged unitary construction of generally standard character as explained above. The member 24 and forward arm portion 27 thus constitute an elongated, essentially cylindrical, arm-like peel assembly; while the part 27 is illustrated as a separable element seated in the hollow end of the body member 24, it will be understood that if desired, this assembly may be conveniently fabricated as, or made into one piece. By virtue of the described arrangement, not only the entire peel assembly of the parts 24 and 27 but also the pusher mechanism 18 carried on the part 27, may all be rocked up and down together about the transverse pivot 26, as viewed in Fig. 2. The peel 27 has a head member 28 which is of generally rectangular contour and which removably engages the lug 23 of the charging container 11, as is more clearly illustrated in Fig. 5.

The pusher mechanism 18 comprises two pusher arms 29 which have head members 17 attached to their respective ends as previously indicated, and which are disposed externally of the peel, in a parallel relation to it at respectively opposite sides. These pusher arms are constructed in a suitably rugged manner, for example with an I beam type of cross section as illustrated in Fig. 4. Each pusher arm 29 carries a rack 30 attached to the top thereof in

order that the pusher arms may be extended relative to the peel, as by means of a reversible motor 31 and its associated gearing. Specifically, pinions 32 engage the racks 30 and are driven through reduction gears 33 and a belt, chain or other drive generally indicated by reference numeral 34, from the motor 31. In other words the motor 31 drives the reduction gears 33 by means of a conventional belt chain or other arrangement which is schematically shown as a covered pear-shaped section 34.

The motor 31 and its associated drive are supported in a framework 35 which is integrally attached to the peel body member 24, as best illustrated in Fig. 3. This framework 35 also carries means of support for the pusher arms 29, such means comprising a pair of rollers 36 at the top of each pusher arm 29, and a single roller 37 underneath each pusher arm. The upper rollers 36 are constructed with an H-shaped cross section, as may be seen in Fig. 4, in order to accommodate the rack 30 within the space formed by the lower arms of the H-shaped configuration. The lower rollers 37, however, are conveniently solid or full-surfaced cylindrical wheels to provide maximum support for the pusher arms 29. In operation when it is desired to extend (or withdraw) the pusher arms 29, the motor 31 is operated which causes the pinions 32 to be driven and hence advances (or retracts) the arms 29 by means of the racks 30.

Fig. 6 illustrates the charging vehicle which supports the peel assembly comprising the forward peel arm 27 (not shown in Fig. 6) and the body member 24 with the pusher mechanism 18 (Figs. 1 and 2). In the illustrated apparatus of Fig. 6, which may be of conventional design but is here shown for completeness of disclosure of the manner in which the novel combination functions, a large supporting framework is arranged to operate or be moved on transverse track rails, one of which is illustrated at 38. The other track rail (omitted for brevity and clarity in the drawings) is conventionally located near the front of the large framework, more or less under the peel arm 27 when it is in the position as illustrated in Figs. 1 and 2. This large framework, which is likewise only fragmentarily shown for the sake of clarity, is supported on the rails by corresponding wheels, of which again, only one is illustrated, e. g. at 48. These tracks run across in front of the furnace 13 (Fig. 1) so that the charging vehicle 25 may be moved from one furnace to one or more others in order that more than one furnace may be charged by this same machine. The described framework of the charging apparatus, which includes the supporting structure (or vehicle) 25 for the bearings of the peel pivot shaft 26 and thus for the peel assembly, also includes means providing for movement of such structure or vehicle toward and away from each furnace, e. g. on suitable tracks which are carried by or with the framework. Single rails of each of two such tracks are fragmentarily illustrated at 39 and 39', the vehicle 25 itself being supported on these rails by wheels such as indicated by reference numerals 40 and 40'. There are also horizontal guide wheels such as shown at 41 to maintain the vehicle stable within its framework.

The vehicle framework 25 supports the peel and pusher mechanism as previously indicated, by means of the shaft 26. In order to rock the peel and pusher mechanism about this shaft, i. e. to elevate and depress the peel and pusher heads 28, 17, the body member 24 extends back and is attached to a crank 42 by means of a connecting link 43. When the crank is rotated, the body member 24 and necessarily also the forward peel arm and pusher mechanism, will be rocked up and down as illustrated by the dotted line positions 24a and 43a of the member 24 and the link 43. The crank 42 is mounted on and driven by a shaft 44 which in turn is driven by a gear 45. The motive power to drive the gear 45 is transmitted through reduction gears 47 from a suitable reversible motor, which may be considered, in Fig. 6, to be concealed behind certain bearing-supporting structure 49.

The exploded view as shown in Fig. 5 illustrates more clearly how the charging box 11 is constructed and operated. As seen, the false back 14 is a separate part from the container itself and carries the lugs 16 which are adapted to be engaged by the head members 17 of the pusher arms 29. For holding a heavy load of scrap, the open-ended box or container itself is solidly constructed with the lug 23 adapted to be engaged by the head member 28 of the peel. As shown, the lug 23 has a downwardly-open, upwardly-closed, box-like configuration into which the peel head 28 removably but non-rotatably fits, the rear or outer side of the lug having a wide notch to accommodate the shank of the peel. The lugs 16 conveniently have a similar configuration to receive the pusher heads 17, so that upon engagement of the latter the pushers hold the false back (against appreciable horizontal displacement of the back relative to the pushers) and can both advance and retract horizontally in the box.

It will now be clear that when the head member 28 of the peel is brought up into engaging relation with lug 23, the head members 17 will simultaneously engage lugs 16; that is, the pushers 27 are initially positioned with their heads 17 and the peel head 28 in horizontal alignment so that upon swinging the peel assembly upward (from a lower and more forward position than actually shown in Fig. 2) the three head members are carried vertically into effective engagement with the corresponding lugs, the box 11 having been loaded with the false back 14 in rearmost position, e. g. resting against the fixed back structure 23'. Thereupon the container 11 may be lifted from its car 20 (Fig. 2) and carried into a desired location within the furnace. Then the pusher mechanism 18 is operated and the pusher arms 29 extended so that false back 14 is slid forward across the bottom of the box 11 to discharge the contents. Following this operation the arms 29 are retracted, returning the false back 14 to its original position, and by reverse operation of the peel the box 11 is withdrawn from the furnace and re-seated on the car. It will be noted that the guide support members 15 for the false back 14 advantageously consist of simple triangular-shaped plates which are so attached to the forward side of the false back 14 that it will be supported and may stand in a vertical position without other support.

Operation

To review the operation of the apparatus a charging sequence will be followed in a general way. The charge box 11, having been filled with scrap or other material to be charged into the furnace, is carried in front of the furnace door 12 by means of a car 20 which travels along the rails 21. When the box is in position in front of the furnace door 12, the charging vehicle is correspondingly positioned in front of the furnace door so that the peel 27 is in line with the lug 23 on the box. Then the vehicle is brought toward the furnace while the peel 27 is rocked down enough to clear the flanges of the lug 23. As explained above, after the peel head 28 has been elevated into engagement with lug 23, the peel 27 is further raised to lift the charging box 11 off car 20 in preparation for carrying the charge container into the furnace. It has also been explained that at the same time as the head 28 engages the lug 23, the head members 17, being positioned on a line with the head member 28, simultaneously engage the lugs 16 on the false back 14.

Now the charging vehicle is moved forward in order to carry the charge box 11 into the furnace to a desired position, and the pusher mechanism 18 is operated so as to cause pusher arms 29 to move forward and carry false back 14 across the bottom of the box pushing the material to be charged out of the box into the furnace. Then the pusher arms are withdrawn and the vehicle is backed away from the furnace to return the box 11 to its posi-

tion in front of the furnace where it may be replaced on car 20 and disengaged from the peel and pusher arms. Thereafter the operation may be repeated with a second car and so on until the charge of the furnace has been completed.

It will be seen that the invention, especially as exemplified in the described apparatus, fulfills the various objects set forth above and affords particularly convenient means for charging furnaces with scrap or the like. The entire charging operation is greatly expedited in the ways explained, with great economy of time, equipment and other expense. The deposit of loads in the furnace is more accurately achieved; indeed if it is desired to distribute the contents of the charging box 11 (instead of pushing the load off into a single pile or heap), the operator need merely move the vehicle (and peel) rearwardly and thus cause the box to recede, while at the same time the pushers are driven forwardly (relative to the peel) to empty the box. All of the stated advantages are achieved with a mechanism that is extremely simple and rugged, involving no special attachments or internal moving parts in the peel 27 or its head 28, and utilizing a charge box 11 which, with its essentially unitary false back 14, has no complex mechanical elements to become deranged by the heavy use to which equipment of this sort must be put. Finally, the operations of engaging the peel and pusher means with the box and its false back, and of disengaging these elements, are fully simplified, being essentially no more than are involved in corresponding operations with the prior, conventional types of small charging boxes.

A specific example of this invention has been described in detail, but it is not to be taken as in any way limiting the invention, which may be embodied in other forms without departure from its spirit.

We claim:

1. In furnace charging apparatus the combination comprising charging vehicle means having a peel pivotally attached thereto, said peel having a single head member and being adapted to rock up and down as said peel is rotated about its pivot, charge container means having a lug adapted to be engaged by said head member for supporting said charge container means solely on said head member, said charge container means having false back means for discharging said container means, said false back means having rearwardly accessible lug means, and pusher means located externally of said peel and engageable with said lug means for moving said false back means to discharge said container means, said peel and pusher means being mounted to the moved together, said container lug and said lug means and said peel head member and said pusher means being constructed and arranged for simultaneous operative engagement of said head member and pusher means respectively with the lug and lug means upon simultaneous displacement of said peel and pusher means into said relation of engagement.

2. In furnace charging apparatus the combination comprising charging vehicle means having a peel pivotally attached thereto and being movable horizontally toward and away from said furnace, said peel consisting of a single unitary arm having a head member and being adapted to rock up and down as said peel is rotated about its pivot, charge container means having back structure carrying central lug means adapted to be engaged by said head member for supporting the container means on the peel, said container means having false back means for discharging said container means, pusher means located externally of said peel and comprising a plurality of pusher members adapted to engage said false back means and discharge said container means, said peel and pusher means being mounted to be moved together, said central lug means and said false back means and said peel head member and said pusher means being constructed and arranged for simultaneous operative engagement of said head member and pusher means respectively with the lug

means and false back means upon simultaneous displacement of said peel and pusher means into said relation of engagement.

3. In furnace charging apparatus the combination comprising charging vehicle means having a peel pivotally attached thereto and being movable horizontally toward and away from said furnace, said peel consisting of an arm having a single head member and being rockable up and down as said peel is rotated about its pivot, charge container means having lug means adapted to be engaged by said head member for supporting the container means on the peel, said container means having false back means having two lugs thereon, pusher means located externally of said peel and comprising two pusher members having enlarged end pieces and adapted to engage said false back lugs and slide said false back across said container means to discharge the same, said peel and pusher means being mounted to be moved together, said lug means and said two lugs and said peel head member and said pusher means being constructed and arranged for simultaneous operative engagement of said head member and pusher means respectively with the lug means and two lugs upon simultaneous displacement of said peel and pusher means into said relation of engagement.

4. In furnace charging apparatus the combination comprising charging vehicle means having a peel pivotally attached thereto and being movable horizontally toward and away from said furnace, said peel having a head member and being rockable up and down as said peel is rotated about its pivot, charge container means having lug means adapted to be removably engaged by said head member and false back means having two lugs thereon and support members to maintain said false back means in a vertical position, pusher means located externally of said peel and comprising two pusher members having enlarged end pieces and adapted to engage said false back lugs and slide said false back across said container and return, said peel and pusher means being mounted to be moved together, said lug means and said two lugs and said peel head member and said pusher means being constructed and arranged for simultaneous operative engagement of said head member and pusher means respectively with the lug means and two lugs upon simultaneous displacement of said peel and pusher means into said relation of engagement.

5. In furnace charging apparatus the combination with charging vehicle means having a peel pivotally mounted thereon and being movable horizontally toward and away from said furnace, said peel having a head member and being rockable up and down as said peel is rotated about its pivot, of pusher means located externally of said peel and comprising a pair of arms having enlarged end pieces, said arms being movable relative to but remaining parallel with said peel, charge container means comprising false back means having a pair of lugs thereon, said charge container means having lug means adapted to be removably engaged by said head member, said pair of lugs being adapted to be removably engaged by said enlarged end pieces, all whereby said charge container may be positioned in a desired location within said furnace and said container means may be discharged, said peel and pusher means being mounted to be moved together, said lug means and said pair of lugs and said peel head member and said pusher means being constructed and arranged for simultaneous operative engagement of said head member and pusher means respectively with the lug means and pair of lugs upon simultaneous displacement of said peel and pusher means into said relation of engagement.

6. In furnace charging apparatus the combination with charging vehicle means having a peel pivotally mounted thereon and being movable horizontally toward and away from said furnace, said peel having a head member and being rockable up and down as said peel is rotated about its pivot, of pusher means mounted integrally with but located externally of said peel and comprising a pair of

arms having enlarged end pieces, said arms being movable relative to but remaining parallel with said peel, and charge container means comprising false back means having a pair of lugs adapted to be engaged by said enlarged end pieces and having brace means for holding said false back means upright, said charge container means having lug means for receiving said head member so that said charge container means may be carried by said peel, said peel and pusher means being mounted to be moved together, said lug means and said pair of lugs and said peel head member and said pusher means being constructed and arranged for simultaneous operative engagement of said head member and pusher means respectively with the lug means and pair of lugs upon simultaneous displacement of said peel and pusher means into said relation of engagement.

7. In furnace charging apparatus the combination with charging vehicle means having a peel pivotally mounted thereon and being movable horizontally toward and away from said furnace, said peel having a head member and being rockable up and down as said peel is rotated about its pivot, of a pair of pusher arms having enlarged end pieces, said pair of arms being mounted integrally with but externally of said peel, a charge container having a lug thereon adapted to be engaged by said head member and having a false back with a pair of lugs and a pair of braces on said false back, said pair of lugs being adapted to be engaged by said enlarged end pieces, whereby said pusher arms will operate to discharge said charge container by means of said false back when said pusher arms are extended relative to said peel, said container lug and said pair of lugs and said peel head member and said pusher arms being constructed and arranged for simultaneous operative engagement of said head member and pusher arms respectively with the container lug and pair of lugs upon simultaneous displacement of said peel and pusher arms into said relation of engagement.

8. In furnace charging apparatus, the combination comprising a peel consisting of a single arm structure having a single head for removable engagement with a charging container to support the container, means for moving the peel toward and away from the interior of a furnace, supplemental peel-displacing means to elevate and depress the head of the peel, a charging container having its forward side open and having a false back displaceable between rear and forward positions in the container, lug means on the container to be removably engaged by the head of the peel, pusher means mounted to be moved with the peel and having head means adapted for removable engagement with the false back in the charging container, said pusher means being disposed externally of said peel and said false back having lug means disposed externally of the first-mentioned lug means for removably receiving the pusher head means to hold said false back against horizontal movement relative to the pusher means, and means for moving said pusher means relative to the peel to displace the false back substantially horizontally in the container for discharging said container, said container lug means and said false back lug means and said peel single head and said pusher head means being constructed and arranged for simultaneous operative engagement of said peel single head and pusher head means respectively with the container lug means and false back lug means upon simultaneous displacement of said peel and pusher means into said relation of engagement.

9. In furnace charging apparatus, the combination comprising a peel having a head for removable engagement with a charging container to support the container, means for moving the peel toward and away from the interior of a furnace, supplemental peel-displacing means to elevate and depress the head of the peel, a charging container having its forward side open and having a false back displaceable between rear and forward positions in the container, lug means on the container to be removably engaged by the head of the peel, pusher means carried

on the peel for movement therewith and having head means adapted for removable engagement with the false back in the charging container, said pusher means being disposed externally of said peel and said false back having lug means disposed externally of the first-mentioned lug means for removably receiving the pusher head means to hold said false back against horizontal movement relative to the pusher means, and means for moving said pusher means relative to the peel to displace the false back substantially horizontally in the container for discharging said container, said first and second lug means and said peel head and pusher head means being constructed and arranged for simultaneous engagement of said head and head means respectively with said lug means upon simultaneous, substantially vertical displacement of said peel and pusher means in a predetermined direction relative to the charging container.

10. In a furnace charging apparatus, the combination comprising a peel having a head for removable engagement with a charging container to support the container, means for moving the peel toward and away from the interior of a furnace, means for rocking the peel about a horizontal axis to elevate and depress its head, pusher arm means carried by the peel externally thereof and adapted to be moved therewith by said moving and rocking means, a charging container having its forward side open and having a false back displaceable between rear and forward positions in the container, said container having lug means for removably receiving the peel head, and said false back having lug means and said pusher arm means having head means, arranged for mutual, removable engagement between said head means and with said second-mentioned lug means, said container lug means and said false back lug means and said peel head and said pusher arm head means being constructed and arranged for simultaneous operative engagement of said peel head and pusher head means respectively with the container lug means and false back lug means upon simultaneous displacement of said peel and pusher arm means into said relation of engagement, so that upon movement of said peel to displace its head into engagement with the first-mentioned lug means the head means of the pusher means is simultaneously engageable with the second lug means, and means for moving said pusher arm means relative to the peel for advancing the false back from rear to forward position in the container, to push material out of the container into the furnace.

11. In furnace charging apparatus, the combination comprising a peel consisting of an arm having a single head for removable engagement with a charging container to support the container, means for moving the peel toward and away from the interior of a furnace, supplemental peel-displacing means to elevate and depress the head of the peel, a charging container having its forward side open and having a false back displaceable between rear and forward positions in the container, lug means on the container to be removably engaged by the

5 head of the peel, said container including structure mounting said lug means centrally at the rear of the container, a pair of pusher arms, means carried on the peel for mounting said arms externally of the peel arm at opposite sides of the peel, said pusher arms being movable with the peel and being longitudinally displaceable in said last-mentioned mounting means, each of said pusher arms having a head adapted for engagement with the false back in the charging container, said false back having a pair of lugs disposed to be accessible through the rear of the container at opposite sides of the first-mentioned lug means, for removably receiving the respective heads of the pusher arms to hold said false back against appreciable horizontal movement relative to the pusher arms, and means for simultaneously moving said pusher arms longitudinally relative to the peel to displace the false back substantially horizontally in the container for discharging said container, said lug means and lugs and said peel and pusher heads being constructed and arranged for simultaneous engagement of said heads respectively with said lug means and lugs upon simultaneous upward displacement of said peel and pusher arms from a locality below the rear of the charging container.

12. In furnace charging apparatus the combination with charging vehicle means having a peel pivotally mounted thereon and being movable horizontally toward and away from said furnace, said peel having a head member and being rockable up and down as said peel is rotated about its pivot, of pusher means mounted integrally with but located externally of said peel and comprising a pair of arms having enlarged end pieces, said arms being movable relative to but remaining parallel with said peel, and charge container means comprising false back means having a pair of socket like lugs for receiving said enlarged end pieces, overlapping edges on three sides of said lugs for holding said enlarged end pieces securely after engagement of the enlarged end pieces with the lugs, brace means on said false back means for holding the false back means upright, a third socket like lug centrally located on said charge container means, overlapping edges on three sides of said third lug for holding said peel head member securely after engagement therewith, said three socket like lugs being located to correspond with the peel head member and the enlarged end pieces so that all may be simultaneously engaged and the false back means may be moved horizontally to discharge said charge container means while being carried by said peel.
